BEDSPRING LIFTING DEVICE

Louis Herzog, Brooklyn, N. Y., assignor of one-half to Joseph Miller, Brooklyn, N. Y.

Application April 8, 1937, Serial No. 135,632

5 Claims. (Cl. 5—323)

My invention relates to a lifting device for lifting bed spring frames and mattresses, and the purpose is to provide a very simple device of this character by means of which the bed spring and mattress of a bed may be tilted or rocked on an axis to raise them to an elevated position for the purpose of giving ready access for the cleaning of the floor under the bed as well as to place the bed spring frame in a position for easily 10 cleaning the springs, bed frame etc.

Devices have been proposed for this purpose but the present invention is an improvement over former devices, especially in that the device may be applied to any type of bed and bed spring now 15 in use because the lifting device requires no modification of the bed structure, nor the spring frame structure. On the other hand, the lifting device does not have to be applied at the factory to the bed spring, nor the bed, but it may 20 be attached if desired by the user, and without even the necessity of using tools for the mounting of the device on the bed.

Another object of my invention is to provide a bed spring lifter which will more effectively 25 counterbalance the weight of the spring frame and the parts carried by it and readily hold the spring frame in the raised or tilted position while the floor below the bed is being cleaned, or while the various bed springs and frame are being 30 cleaned.

Another object of the invention is to provide a bed spring lifter which may be mounted entirely on the side beams of the bed, thereby eliminating attachment of any of the parts to any 35 cross members of the bed structure.

Another object of the invention is to provide a bed spring lifter which will permit all cross members of the bed structure, other than the head board and the foot board, to be omitted or removed so that when the bed spring frame is in 40 raised position there will be a full clear space in which to move a mop or other cleaning instrument over the floor beneath the bed.

Another object is to make the bed spring lifter 45 detachable from the bed structure and in a simple manner, so that in case of moving, the lifting device may be detached from the bed frame or from the spring frame, or both, to be readily packed for moving purposes.

Another object is to provide a very simple construction of bed lifter having but few parts, and which will be very simple in operation.

I have shown my invention in two different forms, one of which is adapted to be applied to

a wooden bed structure while the other is adapted to be applied a metal bed frame.

Other objects and advantages of the invention will be set forth in the following detailed description of my invention.

In the drawings forming part of this application,

Figure 1 is a perspective view of a bed to which my invention is applied and showing the device positioned to support the spring frame in elevated position for cleaning purposes.

Figure 2 is a cross sectional view thereof, also showing the device in elevated position as in Figure 1.

Figure 3 is a perspective view showing a bracket for attaching one side of the spring frame to the bed structure.

Figure 4 is a view similar to Figure 2 but showing the spring frame in lowered position or in the position it assumes when the bed is in use.

Figure 5 is a plan view showing one of the brackets, a portion of the spring frame, and the pivotal connection by which the pivoted side of the spring frame is attached to the bed frame, and corresponding with the construction shown in Figures 1 to 4 inclusive.

Figure 6 is an end view of the parts shown in Figure 5.

Figure 7 is a face view of the parts shown in Figure 5, looking at the right hand face of the parts in that figure.

Figure 8 is a sectional view of a portion of the spring frame and bed frame, where the latter is made of metal, and showing in end elevation the means for attaching the pivotal side of the spring frame to the bed frame.

Figure 9 is a detailed sectional view showing the bracket for attaching the device to the side of the bed frame opposite to that to which the device in Figure 8 is attached, and where the bed frame is of metal, and

Figure 10 is a sectional view showing the type of clamp to be used where the longitudinal members of the bed frame are made of tubular metal instead of angular metal.

Fig. 11 is a modified form of clamp for attaching the brackets to the rail strip of a wooden bed frame.

I will first describe the form of device shown in Figures 1 to 7 inclusive. In these figures I have shown a bed structure consisting of head and foot boards 1, 2 and between which are connected the side beams or rails 3, 4 of the bed frame, and where my invention is employed it is not necessary to have any cross members between these

5

55

side rails or beams for the spring frame; and if there are such members on the bed they may be removed if desired when my invention is applied thereto. The spring frame is shown as consisting of a rectangular frame work 5 which may be of one piece and comprising longitudinal members 6, 7 extending parallel along opposite sides of the frame, and cross members 8, 9 connected between the side members which, as stated above, 10 may be formed all of one continuous piece of metal.

The cross bars 10 extend between the side members 6, 7 of the spring frame, and I have shown helical springs 11 mounted on the spring 15 frame and supporting the mattress 12.

It will be understood that the present invention may be used in conjunction with any type of spring frame and any spring system, and any type of mattress.

20 Preferably, the present device is so proportioned that it is spaced some distance from the head board and foot board of the bed structure, to leave a large open space for access to the floor when the spring frame is in elevated position. I 25 employ, preferably, two brackets 13 for supporting one side of the spring frame, arranging them spaced apart lengthwise of the bed, but preferably some distance from the foot and head boards. These bracket devices may be both alike 30 and a description of one will apply to both.

Where the two side beams 3, 4 of the bed frame are made of wood, as shown in Figures 1, 2 and 4, these beams are usually of rectangular construction as shown, with their longest diameter 35 extending vertically. Each bracket 13 consists of a U shaped yoke having a wall 14 which rests against the outer surface of the bed frame beam 3, a wall 15 resting on the top surface of the beam, and a wall 16 extending downwardly and 40 lying against the inner surface of the bed beam 3. These brackets may be slid downwardly upon the beam 3 so that they come to rest in the position shown in Figures 2 and 4 and no bolts or other members are necessary to hold them in 45 place, and so that they will not injure the beam of the bed the part in contact with the bed is covered with soft felt.

There is a bracket 18 like that shown in Figure 3, attached by means of a rivet 17 pivotally 50 to a laterally extending plate 19 on each bracket 13. The bracket 18 has a slot 20 extending inwardly from one end, which is adapted to receive one wall 21 of the angle metal member 7 which forms one of the side beams or rails of the spring frame with the other wall 22 of this angle metal member extending downwardly against the inner side of the portion 23 of the bracket 18 which is bent at right angles to the main portion thereof. The bracket 18 also has a portion 24 bent at right 55 angles to the main portion and this member has two apertures 25 as shown in Figure 3, to receive the pivot pins 26 and 27. The first of these pivot pins pivotally attaches to the member 24 a locking key 28 which, when in the lowered position shown in Figure 6, seats against the vertical web 22 of the bar 7 and holds the angle metal bar of the spring frame with its horizontal web 21 disposed in the slot 20. This holds the spring frame in locked relation with the bracket 18 so 60 that they move together upon the pivot 17. The locking pin 28 may be turned on the pivot 26 to a horizontal or upward position to release the bracket 18 from the bar 21, 22 whenever the device is to be disassembled for the removal of the 65 spring frame from the bed.

As long as the device is in operation upon a bed, the locking member 28 is in the lowered position shown in Figure 6. This forms a very convenient means for assembling the spring frame at this position with the brackets 18 and with the brackets 13 which are applied to one of the side beams of the bed, and no screws or bolts are necessary for assembling and disassembling of the spring frame on the supporting brackets.

On the pivot pin 27 there is pivotally mounted 10 an arm 30 having an offset portion 31^a and this is adapted to be swung up into the raised position shown in Figure 2, to act as a stop to prevent the mattress and upper portion of the spring structure from sliding out of place when 15 the spring frame is to be elevated to the position shown in Figures 1 and 2.

When the bed is in position for sleeping purposes the lever arms 30 may be lowered into the position shown in Figure 4, to be out of the way, 20 or in other words, it need only be elevated when the spring frame is to be lifted. When there are two brackets 13 for supporting the spring frame, there are preferably two arms 30 one for each bracket.

It will be understood that the pivot pins 17 by which the brackets 18 are pivotally connected with the brackets 13 will be in alignment and that this line will form the axis about which the spring frame swings between the lower position 30 shown in Figure 4 and the raised position shown in Figures 1 and 2.

I have shown clamps 31, there being two in the drawings, consisting of two plates connected together by bolts 32, the plates being applied to 35 opposite sides of one of the cross bars 10 of the spring frame, with one bolt 32 above this bar and the other below it, as shown in Figure 2. It is understood that both these clamps are alike.

There is a longitudinally extending rod 33 passing 40 through the free ends of the clamps 31 and adjacent each end of the pivot rod there is pivotally mounted a lever arm 34. These lever arms, each being of the same length, are pivotally connected by the pins 35 with other lever arms 36 45 which are preferably longer than the arms 34. These latter lever arms 36 are pivotally connected with the pins 37 mounted in the lower ends of the downwardly extending members 38 of brackets which are mounted upon the right hand beam 50 4 of the bed frame in Figures 2 and 4. These brackets 39 are attached to the right hand beam 4 of the bed structure in the same manner as the brackets 13 on the left side. Each consists of a vertical wall 40 engaging the outer surface 55 of the right hand beam 4 of the bed frame, of a horizontal wall 41 resting on the top of the beam 4, and a vertical wall 42 extending downwardly and engaging the inner side of the beam 4. From this latter wall there extends horizontally toward the center line of the bed a rest portion 43 on which the longitudinal bar 6 of the spring frame is adapted to rest and the downwardly extending portion 38 to which the lever arm 36 is pivoted is a downward continuation 60 of the portion 43 of the bracket.

There are spiral springs 44 each having one end connected with a pin 45 on the bracket 43 and another end connected with the rod 46 which extends through apertures in the pair of lever 70 arms 36 so that these springs have a tendency to raise the lever arms 36 from the position shown in Figure 4 to the position shown in Figures 1 and 2. There are other spiral springs 47 each having one end connected with the bar 46 and 75

their opposite ends connected with pins 48 which are mounted on the ends of the lever arms 49 which project below the plane of the pivot points 35 of the lever arms 34 in Figures 1 and 2. Preferably, there are straps 50 connected with these same pins 48 which lie parallel and against the face of the lever arms 36 and they are provided with laterally extending pins 51 which are adapted to abut against one edge of each of the lever arms 36 when the spring frame is in the position shown in Figures 1 and 2, to limit the relative rocking motion of the lever arms 36 and 34 to about the position shown in these figures. In other words, they prevent the joined ends of the lever arms 36, 34 from moving upwardly in Figure 2, and thus allowing the spring frame to drop.

Operation

In order to attach the present device to a bed 20 and its spring frame, it is only necessary to apply the brackets shown in Figures 1 to 7 to the side beams of the bed frame by disposing them upon the side beams in the manner shown in the drawings, where they will engage and rest without 25 any bolts or screws for holding them in place, although such may be used if desired. If there are any cross slats or supports on the bed these may be removed if desired to leave the entire space within the bed structure free and open.

30 The clamps 31 are attached to the cross bars 19 of the spring frame. One of the side rails of the spring frame is presented to the bracket 18 so that the horizontal wall 21 of the side rail enters the slot 20 of the bracket member 18 while 35 the locking member 28 is turned up, whereupon this locking member is turned down to hold the member 7 locked to the bracket member 18.

When the bed is in use or in condition for use, the parts will be in the condition shown in Figure 4 where one side of the spring frame is supported by the brackets 13 upon one of the side beams of the bed frame and the other bar 6 of the spring frame rests upon the projecting supports 43 of the right hand bracket 39. The lever arms 34, 36 with their springs are all folded up close to the under side of the spring frame and during this time the springs 47 are drawn out or under tension, and the springs 44 are also drawn out and under tension. No part of the present device need be connected with any cross members of the bed frame if there are any nor with the head board or foot board structures.

To operate the device to give access for cleaning the floor below the bed, or for cleaning the bed springs, the operator may grasp the spring frame at the right side of the bed, as shown in Figure 4, or the front side as shown in Figure 1, and lift this side of the spring frame until the parts are in the position shown in Figures 1 and 2, whereupon complete access may be had to the floor below the bed as well as to the various parts of the bed springs and frame for cleaning purposes. The spring frame and mattress may also be elevated in this manner to allow better circulation of air around the springs and mattress. Before raising the spring frame the abutment arms 39 may be swung from the horizontal into the vertical position so that when the spring frame is elevated to the inclined position one side of the mattress may rest against these arms which will prevent it from sliding off the spring frame. In the operation of raising the spring frame in the manner described, the operator does not have to lift the full weight of the spring frame and mattress because the springs 44 exert a pull-

ing pressure upon the rod 46 and therefore upon the lever arms 36 which pressure tends to move the spring frame into the position shown in Figures 1 and 2, but their strength is not sufficient to completely lift the spring frame and mattress as otherwise it would be necessary to lock the spring frame in lowered position.

The springs 47 are also exerting a pulling tension upon the pins 48 which are connected with the arms 49 of the levers 34. While the bed spring and mattress are in the lowered position shown in Figure 4 the springs 47 have very little effect on the tendency to lift the spring frame and mattress because these springs are almost in alignment with the lever arms 34. However, as soon as the operator starts to lift one side of the spring frame the levers 34 pivot about the pins 35, whereupon the springs 47 exert an increasing pull upon the lever arms 34 and this action is added to the action of the springs 44 and their combined strength may be so designed as to completely lift the spring frame and mattress once the pivotal motion thereof is started by the operator, so that the latter may merely initiate the lifting operation and the remainder of the movement may be carried out entirely by the springs 44 and 47. When the parts reach the position shown in Figures 1 and 2 the pins 51 will strike against the under edges of the lever arms 36 and thus stop the rocking motion of the lever arms 36, 34 after the arms 49 of the latter have passed one side of the pivotal points 35 thereby limiting or setting the positions of the several lever arms so that the spring frame and mattress will remain in the position shown in Figures 1 and 2 while the floor is being cleaned, or while the springs and their frame are being cleaned.

To lower the device back into operative position, shown in Figure 1, the operator need simply 40 press the arms 49 backwardly or press the lever arms 36 backwardly, and pulling downwardly on the right hand side of the spring frame until the lever arms 49 have swung to the other side of the pivots 35 to break the joint, whereupon the operator merely continues to press downwardly on the right side of the spring frame in Figure 2, until the parts have been returned to the position shown in Figure 4. The pressure required on the spring frame to lower the parts to the position shown in Figure 4 is very light as it is merely the difference between the raising effect 45 of the several springs and the weight of the spring frame and mattress.

During the pivotal motion of the spring frame 55 it swings about the pins 17 on the brackets 13. By having the supports 43 extend inwardly some distance from the brackets 39 the spring frame will rest upon these supports even though its width does not correspond exactly with the space 60 between the two beams 3, 4. In other words, the spring frame does not have to correspond exactly with the spacing of the side beams of the bed frame.

The device may be readily detached from the 65 bed by simply lifting the brackets 13, 39 off the bed frame either in conjunction with the spring frame or the brackets may be detached from the spring frame and the bar of the spring frame may be detached from the brackets.

In Figures 8 and 9 I have shown a modification 70 of the bracket devices in order to adapt the present invention to bed frames of metal construction. In Figure 8 I have shown an angle metal member 53 which forms one of the longitudinal 75

members of a metal bed frame and corresponds in position and function with the wooden beam 3 of the first described form. The bracket member 54 is provided with a slot 55 to receive edge-wise therein the horizontal web 56 of this angle metal beam and this bracket is preferably provided with a laterally extending member 57 which engages the under surface of the web 56 of the bed beam and with another laterally extending member 58 engaging the top surface of the web 56. To this latter member there is pivoted at 59 a locking member 60 which when in raised position permits the web 56 to enter the slot 55 and which, when in lowered position, as in Figure 8, engages the left hand surface of the vertical web 61 and locks the bed frame member to the bracket 54. The bracket member 62 which is pivoted to the bracket member 54 on the stud 63 corresponds with the bracket 18 shown in Figure 6 and previously described, and the parts connected therewith, such as the swinging arm 30 for holding the mattress and the pivotal locking member 28 are all the same as in Figure 6.

In Figure 9 I have shown a type of bracket to replace the bracket shown at the right in Figure 4 to adapt it for a bed frame of metal construction. In this view the bracket 64 is provided with a slot 65 to receive the horizontal web 66 of the right hand angular bed frame member. This bracket has a lateral projection 67 adapted to engage the under surface of the horizontal web 66 and a lateral web 68 engaging the upper surface of this same horizontal web. To the latter there is pivotally connected by the pin 69 the locking member 70 which when in lowered position as shown in Figure 9, engages the outer surface of the vertical web 71 and locks the bracket 64 upon the beam. There is a downward projection 72 extending from the bracket portion 64 and the lever arm 36 is pivoted to this downwardly extending projection on the pin 73 in the same manner that the lever arm 36 is connected to the member 43 in Figures 1, 2 and 4. The brackets shown in Figures 8 and 9 adapt the device to a bed frame of metal construction and embody the same principles as are disclosed in the first described form of the invention.

In Figure 10 I have shown a method of attaching the lifting device to a bed frame, the side beams of which are of tubular form. In this form I have shown the tubular member 74 as the longitudinal beam of a bed frame. There are two members 75, 76 pivotally connected with each other at 77 each having an arcuate portion partly surrounding the beam 74 and adapted to be clamped upon this beam by the bolt 78 passing through ears 79 extending laterally from each of the arcuate members. The straight or stem portions 80 projecting from each of the arcuate members 75, 76 lie face to face against each other and they overlap each other. One of these projections is carried out to form an extension 81 which has a pin 82 on which either the bracket shown in Figures 5 and 6 or the brackets shown in Figure 8 is attached. In other respects the construction may correspond with that shown in Figures 1, 2 and 4.

In Figure 11 I have shown a modified form of bracket for attaching the brackets of the lifting device to the rail strip ordinarily present on wooden bed frames, instead of being mounted directly upon the beam of the bed frame. At 83 I have shown one of the rail strips which is attached to the bottom and inner side of the beam 75 84 of the bed frame. The bracket 85 in this

construction consists of a web 86 resting upon the rail strip 83 the web 87 extending downwardly inside the rail strip, and a horizontal web 88 extending under the rail strip. Thumb screws 89 threaded in this lower web 88 are adapted to be screwed up against the under side of the rail strip 83 to hold the clamping member thereon. The bracket 90 has a bottom end 91 extending at right angles thereto and riveted to the upper web of the clamp 85. This bracket 90 extends upwardly along the inner side of the beam 84 and its top end is provided with the rivet 92 on which the bracket 93 is pivotally mounted. This latter bracket 93 and the parts carried by it correspond in construction and function with the bracket 18 shown in Figure 3.

From the above it will be apparent that I have provided a spring lifting device which gives complete access to the floor below the bed for cleaning, as well as full access to the spring for cleaning. The device is simple and effective and while it may be factory built on the spring frame, it is also adapted to be applied to the spring frame and bed frame by the user and without the use of tools. The device in no way injures nor mars the bed frame. It also permits all cross members of the bed frame intermediate the head and foot boards to be removed if desired. The device requires no attachment to either the head board or the foot board.

Having described my invention, what I claim is:

1. In a bed spring lifting device, the combination of means for hinging one side of the bed spring to one side of a bed frame, a bracket on the other side of the bed frame having an arm projecting therefrom and providing a support for the bed spring when in lowered position, a pair of levers, one of said levers being pivoted at one end to the other lever at an intermediate point thereof and one of said levers being pivoted to the bracket arm below the plane of the supporting face of the arm, and the other of said levers pivoted to the under side of the bed spring, tension means between the end of the intermediately pivoted lever and the other lever adapted to urge said levers into straightened relation when the bed spring is in a downward position, and tension means between the bracket to which the lever is pivoted and said tension means adapted to urge said lever in an upward direction.

2. In a bed spring lifting device, the combination of means for hinging one side of the bed spring to one side of a bed frame, a bracket on the other side of the bed frame having an arm projecting therefrom and providing a support for the bed spring when in lowered position, a pair of levers, one of said levers being pivoted at one end to the other lever at an intermediate point thereof and one of said levers being pivoted to the bracket arm below the plane of the supporting face of the arm, and the other of said levers pivoted to the under side of the bed spring, a spring attached at one end to the end of the intermediately pivoted lever and at the other end to the other lever adapted to urge said levers into a straightened relation when the bed spring is in a downward position, and a spring attached at one end to the other lever and the bracket to which said lever is pivoted and said spring adapted to urge said lever in an upward direction.

3. A bed spring lifting device as claimed in claim 1, wherein the intermediately pivoted lever is pivotally connected to the bed spring and the

other lever pivotally connected to the bracket arm.

4. In a bed spring lifting device brackets adapted to be mounted on the side members of a bed frame and each bracket having a laterally extending arm and the arm of one bracket to be engaged by and support the bed spring when in lowered position, means for hinging the bed spring at one side to the arm of the other bracket, a pair of levers one lever pivotally connected at one end to the other lever at a point intermediate the ends of said latter lever, and one lever pivotally connected to the bed spring to extend below the same and the other lever pivotally connected to the arm of the bracket mounted on the side member of the bed frame opposite to that on which the bracket is mounted to the arm on which

the spring is hinged, tension means between the pivoted connection of the levers adapted to urge said levers into a straightened relation when the bed spring is in a downward position, and tension means between the one lever and the bracket to which it is connected adapted to urge said lever in an upward direction. 5

5. In a bed spring lifting device as claimed in claim 4, wherein the means to hinge the bed spring to the one bracket comprises a member fixed to the frame of the spring pivoted to the bracket, a lever pivoted on said member adapted in one position to extend longitudinally of the bed spring and in another position thereof to extend upwardly from said member transversely of 10 the side of the bed spring. 15

LOUIS HERZOG.
